DESIGN FOR A BASE FOR A PERMANENT WAVING MACHINE

John Darby, Westfield, and Linden A. Thatcher,
Belleville, N. J., assignors to Beauty Utilities,
Inc., Newark, N. J., a corporation of Delaware

Application September 1, 1933. Serial No. 49,181

Term of patent 7 years

To all whom it may concern:

Be it known that we, JOHN DARBY, a resident of Westfield, in the county of Union and State of New Jersey, and LINDEN A. THATCHER, a resident of Belleville, in the county of Hudson and State of New Jersey, both citizens of the United States, have invented a new, original, and ornamental Design for a Base for a Permanent Waving Machine, of which the following is a specification, reference being had to the accompanying drawing, forming part thereof.

Fig. 1 is a perspective view of a base for a permanent waving machine, showing our new design, and

Fig. 2 is a side elevation of the base shown in Fig. 1.

We claim:

The ornamental design for a base for a permanent waving machine, as shown.

JOHN DARBY.
LINDEN A. THATCHER.
